DESIGN FOR A CARPET.

SPECIFICATION forming part of Design No. 15,438, dated October 7, 1894.

Application filed August 6, 1894. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

The face of the design is loosely filled in with various disconnected running groups of flower and leaf figures. Bell and star shaped flowers predominate, all as clearly shown in the photograph.

I claim—
